(57) **CLAIM**

The ornamental design for an automobile tire, as shown and described.

DESCRIPTION

FIG. 1 is a perspective view of an automobile tire showing the new design;

FIG. 2 is a front view of the automobile tire shown in FIG. 1, it being understood that the tread pattern repeats uniformly throughout the circumference of the tire;

FIG. 3 is a rear view of the automobile tire shown in FIG. 1; FIG. 4 is a left side view of the automobile tire shown in FIG. 1;

FIG. 5 is a right side view of the automobile tire shown in FIG. 1; and,

FIG. 6 is a partial front view of the automobile tire shown in FIG. 1, shown at an enlarged scale.

The broken lines in FIG. 6 depict the boundary of the figure and form no part of the claimed design.
